UNITED STATES PATENT OFFICE.

AUGUST W. KURZ, OF CLEVELAND, OHIO.

DESIGN FOR A CATCH-BASIN INLET.

SPECIFICATION forming part of Design No. 35,187, dated October 15, 1901.

Application filed August 23, 1901. Serial No. 73,104. Term of patent 7 years.

To all whom it may concern:

Be it known that I, AUGUST W. KURZ, a citizen of the United States of America, and a resident of the city of Cleveland, in the 5 county of Cuyahoga and State of Ohio, have invented and produced a certain new and original Design for Catch-Basin Inlets, of which the following is a specification.

The leading feature of my design consists 10 in the shape of the main of a catch-basin inlet, as shown in the accompanying drawing.

A represents the top of my new inlet, which in general contour is oblong. In detail the outline of the top A is made up of four sides 15 or lines, three of which are straight and one circular. The latter or circular line is located at one of the ends of the top A, and the sides thereof are parallel and are tangent to the circular end, and the other or opposite 20 end is a straight line at right angles to the sides. The front, side, and back walls extend downward along the periphery of the top A. The said walls are partly approximately vertical and partly inclined, so as to 25 make the bottom of the inlet over all larger than the top. The front wall B lies in a plane practically at right angles to the top and is similar in shape to the letter U inverted. About one-seventh of the way back 30 from the front the side walls C are likewise practically vertical with respect to the main of the inlet. The remaining portion E of the side walls slants outwardly from the top to the bottom of the inlet, and part of the back wall,

or that portion of the inlet that extends 35 downward about one-third the distance down along the circular periphery of the top A, has the same slant as the portion E of the side walls, forming a slightly-conical surface G the said one-third distance down, and the remaining 40 two-thirds distance down the inclined surface H is warped. This surface is described by beginning on the sides tangent with the inclined portion E, extending around the back with increasing inclination until the 45 extreme back is reached, where the inclination is greatest, or about forty-five degrees. Along the bottom of the inclined portion E and the bottom of the back H in a plane parallel to the top there is an outwardly-projecting 50 portion F, extending outwardly practically the same distance the entire length of F. There are two openings into the shell or main of the inlet. One, A', in the top is a circular opening which is concentric with the 55 circular end of the top A, while the other extends over the entire bottom of the inlet and upward into the front end B of the inlet, as shown.

What I claim is—

The design for a catch-basin inlet, as herein shown and described.

Signed at Cleveland this 15th day of August, 1901.

AUGUST W. KURZ.
